UNITED STATES PATENT OFFICE.

GEORGE VALIANT, OF TORONTO, ONTARIO, CANADA.

SHOE.

1,128,391.

Specification of Letters Patent. Patented Feb. 16, 1915.

Application filed January 13, 1906. Serial No. 295,978.

To all whom it may concern:

Be it known that I, GEORGE VALIANT, of the city of Toronto, in the county of York, in the Province of Ontario, Canada, have invented certain new and useful Improvements in Shoes, of which the following is the specification.

My invention relates first to a shank curve-forming, sustaining or stiffening device, second a ventilating appliance and third, a combined ventilating and shank curve-forming, sustaining and stiffening device; either feature being perfect in its function independent of the other, but each 10 equally important as a separate improvement in shoe construction, hence I desire to secure claims protecting my invention in the performance of these functions separately and jointly.

20 My invention also relates to improvements in ventilated shoes and the object of the invention is to provide a shank stiffener combining the utilities of stiffening and effectually ventilating a shoe, and also to furnish a means by which shoes not originally designed for ventilation may be 25 readily converted into ventilated shoes without necessitating introducing into such un-ventilated shoe any cumbersome ventilating 30 appliances, which among other disadvantages necessitate a larger shoe being worn than the wearer would otherwise require, and a further object is to obviate the necessity for the use of channels, air ducts, 35 springs within channels and other methods for introducing air between the soles and yet allow my ventilating shank stiffener in case such appliances are preferred to be used with any and all of them.

40 My invention consists of a ventilating shank comprising a retaining member or members and a perforated movable portion to register with perforations through the shank of the shoe.

45 Figure 1, is a perspective view of a shoe showing it reversed and partially broken away in order to exhibit the position of my invention in the shank. Fig. 2, is an enlarged perspective detail of a portion of the shank showing my improvement. Fig. 3, is a cross section through the heel and shank and inner end of the retaining plate. Fig. 4, is a cross section through the shank and my device.

50 55 In the drawings like letters of reference indicate corresponding parts in each figure.

A is a shoe and A' the shank portion thereof.

B is a series of perforations preferably in a row.

C is a recess in the shank in the outer portion thereof and having a step around the edge thereof.

D is a plate of spring metal having a corresponding number of perforations D' arranged in a row corresponding to the perforations B and at the same distance apart. The plate D is provided with a knob D² for manipulating the plate and with a curved engaging end D³.

E is the retaining plate, which is fastened on the step C' around the recess C by nails or any other suitable fastening. The plate E is provided with a row of perforations 2 corresponding in number and substantially 70 registering with the perforations B in the shank. The rear end of the plate E is provided with two alined recesses E' stamped or otherwise formed up in the plate and with one of which the curved end D³ is designed to engage. The rear end of the retaining plate E is also provided under the heel with bent edges E² which are designed to retain the plate in position and obviate any undue pressure on the heel binding the 75 movable plate in position.

F is a strip of fine wire cloth, which is located on the inside of the shank of the shoe and adapted to cover the perforations B.

G is the inner lining of the shoe, which is provided with a longitudinal opening G' or perforations, if desired, designed to always leave the perforations B open and free except for the wire cloth. The lining G serves 90 to cover the edges of the wire cloth and thereby prevent it from being uncomfortable to the foot of the wearer of the shoe.

While this describes my invention as I 95 preferably make it, it will be readily seen that my object may be accomplished in a variety of ways without departure from my invention.

When it is desired to have perfect and free ventilation of the shoe the knob D² is 105 moved so as to bring the movable plate D and the perforations D' thereof to register with the perforations B and 2, and in which position it is retained by the curved end D³ of the plate engaging with the front recess E'.

Whenever it is desirable to exclude mois-

ture the knob D² may be readily moved, so as to bring the movable plate into such a position as to close the perforations.

I am not aware of any means having hitherto been adopted by which a turn or single soled shoe may be ventilated without the introduction of an internal ventilating appliance which at once defeats the object of having a single soled shoe. By the use of 10 my invention this difficulty is entirely overcome.

I am aware that shoes have been ventilated by means of holes extending through the upper and also through the shank, and while 15 these shoes may provide more or less ventilation they fail to provide protection against the entrance of moisture through these ventilating holes when such protection is necessary, and this my invention effectually makes 20 provision for.

While my ventilating shank stiffener is a perfect ventilating appliance it also gives an additional value to the shoe through its utility as an effective stiffener and arch preserving device which it is practically impossible to produce in the ordinary methods of shoe-making, and I desire to emphasize the value of this feature of my invention.

Where it is desired to use the appliance exclusively as a shank curve-forming, sustaining or stiffening device it is applied without reference to the ventilating holes.

To attain the stiffness necessary to preserve the shape of the shank of a shoe the usual method is to introduce between the soles either steel, wood, or other stiffening substances that are either bulky or liable in wear to break and in breaking destroy the appearance and usefulness of the shoe, but in 40 the event of my ventilating shank stiffener being damaged from any cause, it being applied to the outside of the sole, instead of inside the shoe, or between the soles, may be readily and inexpensively replaced.

45 My shank stiffener will also furnish a means whereby an ordinary shoe having the shank damaged as aforesaid may be restored to its former shape and usefulness with the additional value to such shoe of the ventilating feature comprised in my invention.

50 My ventilating shank is also particularly valuable in use in connection with rubber-soled sporting and other shoes both as furnishing a shank stiffener and also as a means of ventilation, neither of which results have been attainable under any methods hitherto adopted in making such shoes.

While I have enumerated the principal

features of utility, durability and general improvement comprised in my invention, it 60 also adds value to the appearance of a shoe in furnishing a permanent shank decoration or finish.

While I prefer to make my ventilating shank stiffener of metal any other suitable 65 material may be used.

What I claim as my invention is:

1. The combination with a shoe having a shank provided with a series of perforations extending longitudinally thereof, of a strip 70 affixed to the outer side of said shank and longitudinally thereof, said strip being adapted to be slid longitudinally and to flexibly conform to the arch of the shank, and said strip having a series of perforations 75 adapted to register with the perforations of the shank in one position of said strip.

2. The combination with the shank of a shoe, of a shank stiffener extending longitudinally on the outside of the shank, and a 80 supplemental stiffener arranged to slide longitudinally upon the aforesaid stiffener and retained in position thereby as specified.

3. In a ventilated shoe, the combination with a sole having a perforated shank, of an 85 exterior arch supporting ventilating shank stiffener comprising a retaining member fixed to the outer side of said shank and a perforated metal strip adapted to slide between said fixed member and the perforated shank, 90 the retaining member having perforations permanently registering with the perforations in the shank, and the sliding member having perforations adapted to be brought into register with the perforations in the 95 shank as specified.

4. In a ventilated shoe an outer sole having a depression in the outer side of its shank and perforations in said depression extending through the sole, and an exterior arch-supporting ventilating shank stiffener comprising two perforated strips, one affixed to the outer side of the outer sole and having its perforations registering with the perforations in the shank and the other adapted to 100 slide above said fixed strip in said depression to register its perforations with the perforations in said shank and both strips flexibly conforming to the longitudinal and lateral curves of the shank of the shoe as specified. 110

GEORGE VALIANT.
